UNITED STATES PATENT OFFICE.

NATHANIEL MARCUS SHINN, OF PHILADELPHIA, PENNSYLVANIA, ASSIGNOR TO ROBERT DORNAN AND THOMAS BENTON DORNAN, OF PHILADELPHIA, PENNSYLVANIA, COMPOSING FIRM OF DORNAN BROTHERS.

WARP-CROSSING MECHANISM FOR LOOMS.

SPECIFICATION forming part of Letters Patent No. 761,416, dated May 31, 1904.

Application filed June 13, 1903. Serial No. 181,396. (No model.)

To all whom it may concern:

Be it known that I, NATHANIEL MARCUS SHINN, a citizen of the United States, residing at Philadelphia, in the county of Philadelphia and State of Pennsylvania, have invented certain new and useful Improvements in Warp-Crossing Mechanism for Looms, of which the following is a specification, reference being had therein to the accompanying drawings.

10 My invention relates to looms, and more particularly to mechanism for crossing or laterally deflecting the warp-threads.

The object of my invention is simplicity of construction and effectiveness of operation and the production of a stationary device that automatically accomplishes the crossing of the pile warp-threads over stationary pile-wires to form pile.

According to my invention a stationary reed is provided in addition to the lay and the warp-crossing mechanism enters the dents of the stationary reed, this stationary reed effecting the guiding and positive control of the warp-crossing mechanism.

25 According to my invention stationary longitudinal pile-wires are employed and deflected guide-surfaces are provided upon the stationary pile-wires and arranged in the paths of the pile warp-threads so as to effect the 30 lateral deflection and crossing of the threads during the up and down movements of the threads.

Also according to my invention the laterally-deflected guide-surfaces on the longitudinal pile-wires enter the dents of the stationary reed and constitute the crossing means therein and coact therewith to effect the crossing of the threads.

I will now describe the construction of a 40 pile-fabric loom embodying my invention, as illustrated in the accompanying drawings, and will thereafter point out the same in claims.

Figure 1 is a longitudinal vertical section showing the principal operative parts of the 45 loom. Fig. 2 is an enlarged broken side elevation in partial section. Fig. 3 is a rear view of the stationary reed, and Fig. 4 is a

plan view of several stationary pile-wires with the stationary reed in section.

In the drawings only so much of the loom 50 is shown as is necessary to illustrate its operation.

The warp-threads *a*, *b*, *c*, *d*, and *e* are controlled by a figuring-harness comprising cords 7, 8, 9, 10, and 11, which are actuated by 55 suitable jacquard or other mechanism. The binder-warp *f* and *g* and a stuffer-warp *h* are controlled by heddles 12, 13, and 14, respectively.

The lay 1 is carried on swords 2 on a rock-shaft 5 and is actuated through connecting-arms 4 by cranks 3 on the main shaft 6. The movable reed 15 may be of any suitable construction. The stationary pile-wires 16 are clamped at their front ends upon a cross-bar 60 17 and extend rearwardly so as to enter the dents 18 of the stationary reed 19, which is of any convenient construction.

According to my invention the stationary pile-wires have attached thereto at their rear ends laterally-deflected 70 surfaces or cams which enter and resiliently close the dents of the stationary reed and positively guide the warp-threads lifted to form the pile so that they pass upward on one side of the stationary pile-wires between the upper-deflected cam and the reed and downward on the other side thereof between the lower-deflected cam and the reed and are thus laterally deflected and looped or crossed over the stationary pile-wires automatically between 75 80 the dents of the stationary reed by the operation of raising and lowering the warp-threads.

In the device illustrating my invention shown in the drawings two oppositely-projecting cam faces or guides are provided, one 85 above the other within each dent of the stationary reed, so that the cams that guided the pile-forming warp-threads in the downward movement of one pile-forming operation will guide the warp-threads lifted for the next 90 pile-forming operation in their upward movement, as shown in dotted lines in Fig. 3, and thus successive piles will be crossed or looped over the pile-wires. To further assist in the

pile-forming operation, the rearward position of the stationary pile-wires is inclined upward to gradually approach the deflecting or cam faces of the crossing device, thereby forming an additional guide for the looped pile-thread. Furthermore, by this construction the stationary pile-wires are at all times removed from possible contact with the shuttle.

In Fig. 1 the lay is shown in extreme forward position and the figuring warp-thread *e* lifted to form pile and ready for a downward movement of the jacquard mechanism or harness when the pile-thread will be crossed from right to left.

Fig. 2 represents the position of the threads after the pile-loop has been formed. The forward end of the stationary pile-wires is inclined and is provided with a pile-cutting edge.

It is obvious that any of the figuring-threads may be lifted to form pile and that the figuring-threads may be controlled by any suitable means and that various modifications may be made in the details of construction within the spirit and scope of my invention.

What I claim, and desire to secure by Letters Patent, is—

1. In a loom, the combination with a lay and means for raising and lowering the warp-threads and forming the sheds, of a stationary reed and warp-crossing mechanism entering the dents of the stationary reed.

2. In a loom, the combination, with a lay and means for raising and lowering the warp-threads, of a stationary reed and laterally-deflected guide-surfaces entering the dents of the stationary reed.

3. In a loom, the combination, with a lay and means for raising and lowering the pile-forming threads and forming the sheds, of stationary longitudinal pile-wires and laterally-deflected guide-surfaces on the stationary pile-wires.

4. In a loom, the combination, with a lay and means for raising and lowering the pile-forming threads and forming the sheds, of a stationary reed and longitudinal pile-wires and crossing means for the pile warp-threads arranged to coact with the stationary reed and longitudinal pile-wires.

5. In a loom, the combination, with a lay and means for raising and lowering the pile-forming threads and forming the sheds, of a stationary reed and longitudinal pile-wires and laterally-deflected guide-surfaces arranged to coact with the stationary reed and longitudinal pile-wires.

6. In a loom, the combination with a lay and means for raising and lowering the pile-forming threads and forming the sheds, of a stationary reed and stationary longitudinal pile-wires provided with laterally-deflected guide-surfaces.

7. In a loom, the combination with a lay and means for raising and lowering the pile-forming threads and forming the sheds, of a

stationary reed and stationary longitudinal pile-wires and crossing means for the pile warp-threads carried by the stationary pile-wires and entering the dents of the stationary reed.

8. In a loom, the combination with a lay and means for raising and lowering the pile-forming threads and forming the sheds, of a stationary reed and stationary pile-wires and laterally-deflected guide-surfaces carried by the stationary pile-wires and entering the dents of the stationary reed.

9. In a loom, the combination with a lay and means for raising and lowering the pile-forming threads and forming the sheds, of a stationary reed, stationary pile-wires and resilient crossing means between the dents of the stationary reed.

10. In a loom, the combination with a lay and means for raising and lowering the pile-forming threads and forming the sheds, of a stationary reed and stationary pile-wires provided with crossing means penetrating and resiliently closing the dents of the stationary reed.

11. In a loom, the combination with a lay and means for raising and lowering the pile-forming threads and forming the sheds, of a stationary reed and stationary pile-wires provided with resilient guide-surfaces penetrating and closing the dents of the stationary reed.

12. In a loom, the combination with a lay and means for raising and lowering the pile-forming threads and forming the sheds, of a stationary reed and stationary longitudinal pile-wires upwardly and rearwardly inclined and provided with oppositely-arranged laterally-deflected guide-surfaces entering the dents of the stationary reed, substantially as set forth.

13. In a pile-fabric loom the combination with means for controlling the warp-threads, of longitudinal pile-wires rigidly attached to the front portion of the loom-frame and extending backward therefrom in planes parallel with the warp and provided at their free ends with laterally-deflected and upwardly-projecting portions.

14. The combination with means for controlling the warp-threads, of pile-wires arranged longitudinally therewith and forming a rigid attachment of the loom-frame, the pile-wires having portions which lie practically in the same plane with the fabric being woven and having their free ends extended upward and provided with laterally-projecting portions.

15. In a pile-fabric loom the combination with means for controlling the warp-threads, of longitudinal pile-wires rigidly attached to the front portion of the loom-frame and extending backward therefrom in planes parallel with the warp and each provided at its free end with a laterally-deflected and upwardly-projecting portion.

16. The combination with means for controlling the warp-threads, of pile-wires arranged longitudinally therewith and forming a rigid attachment of the loom-frame, each of 5 the pile-wires having a portion which lies practically in the same plane with the fabric being woven and having its free end extended upward and provided with a laterally-projecting portion.
- 10 17. In a loom the combination with a lay and means for raising and lowering the pile-forming threads and forming the sheds, of stationary longitudinal pile-wires provided with oppositely-arranged laterally-deflected guide-surfaces.
- 15 18. In a loom the combination with a lay and means for raising and lowering the pile-forming threads and forming the sheds, of stationary longitudinal pile-wires provided with 20 upwardly and downwardly projecting portions having oppositely-arranged laterally-deflected guide-surfaces.
- 20 19. In a loom the combination with a lay and means for raising and lowering the pile-forming threads and forming the sheds, of stationary longitudinal pile-wires upwardly and 25 rearwardly inclined and provided with laterally-deflected guide-surfaces at their rear ends.
- 25 20. In a loom the combination with a lay and means for raising and lowering the pile-forming threads and forming the sheds, of stationary longitudinal pile-wires upwardly and rearwardly inclined and provided at their rear ends with upwardly and downwardly projecting portions having laterally-deflected guide-surfaces.
- 30 21. In a loom the combination with a lay and means for raising and lowering the pile-forming threads and forming the sheds, of stationary longitudinal pile-wires upwardly and rearwardly inclined and provided at their rear ends with laterally-deflected guide-surfaces.
- 35 22. The combination with means for controlling the warp-threads, of pile-wires arranged longitudinally therewith and forming a rigid attachment of the loom-frame, each of the pile-wires having a portion which lies practically in the same plane with the fabric being woven and having another portion in rear thereof upwardly and rearwardly inclined 40 and provided with a laterally-projecting portion.
- 45 In testimony whereof I have affixed my signature in presence of two witnesses.
